UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR AND DOOR MECHANISM THEREFOR.

Application filed September 21, 1926. Serial No. 136,807.

My invention relates to improvements in dump cars and door mechanisms therefor.

Heretofore, it has been customary in the art of dump car construction to employ dump doors and a self-locking door mechanism associated therewith wherein the operating shaft has been disposed above the level of the doors when the latter are in closed position. Such constructions have necessitated providing a shield or inclined portion within the body of the car, to cover the shaft and mechanism. The disadvantages of such prior constructions are that certain of the load-carrying capacity of the car is taken away and further, there is constant danger of the shielding or protecting plates being bended in or distorted so as to interfere with the proper operation of the door mechanism.

One of the objects of my invention is to provide a dump car arrangement and operating mechanism for the doors thereof so arranged that the operating shaft and mechanism may be disposed below the normal level of the car floor without the necessity of providing shielding plates that would be subject to the disadvantages above indicated. More specifically, an object of my invention is to provide an arrangement of the type just indicated wherein may be employed a self-locking door operating mechanism which will be protected from injury, even though disposed below the level of the car floor by certain portions of the car structure, which are normally incorporated therein and which afford a much stronger protection than that heretofore available in arrangements of this general character.

Further objects of my invention are: To provide a door operating arrangement, preferably of the self-locking type, characterized by the fact that the same presents a minimum obstruction to the discharge of the load when the doors are opened; to provide a door structure and operating mechanism therefor which will not only be of rigid and efficient construction, but which will be compactly arranged with ample clearance between the moving door and the door operating mechanism; to provide an arrangement wherein the desired large door opening is provided with ample clearance between all parts of the door structure and the rail, notwithstanding that the operating shaft of the mechanism is located below the level of the door when the latter is in closed position, to provide novel, relatively

inexpensive, and efficient bracing means for the door proper; and to provide a novel shaft rotating and locking means.

Other and further objects of the invention will more clearly appear from the description and claims hereinafter following.

In the drawings forming a part of this specification, Figure 1 is a side elevation of a portion of a gondola type of car showing two dump doors with my improvements embodied therein, certain parts of the structure being broken to more clearly show the parts. Figure 2 is a plan view of the construction shown in Figure 1, approximately one-half of the car, transversely, being shown. Figure 3 is a transverse vertical sectional view through the car taken on a line corresponding substantially to a line 3—3 of Figure 2, part of the door hinge brace being cut away. Figure 4 is a sectional view on an enlarged scale of the portion of the car showing the shaft operating and locking means as viewed on line 4—4 of Figure 1. Figure 5 is a transverse sectional view similar to Figure 3 except that the door is shown in a partially opened position. Figure 6 is a transverse sectional view similar to Figure 3 except that the door is shown in the fully opened position.

In the drawings, A denotes broadly, the center sill of the car, B the crossbeams, C a portion of the side wall of the car, D dumping doors hinged to the center sill, E door raising and supporting mechanism; F door operating shaft rotating and locking means; and G indicates the upper portion of one of the rails.

The centersill A of the car preferably includes a plurality of reinforced channels 10 with a surmounting cover plate 11. The crossbeams B of the car are each preferably formed of diaphragms 12 extending outwardly from the centersill of the car to the respective sides. Top and bottom cover plates as indicated at 13 and 14, respectively, tie the diaphragms across the plane of the centersill and diaphragm members 110 disposed between the center sills act as spacers for the channels 10—10.

Each side wall C of the car includes a longitudinally extending lower chord member 15 preferably in the form of a heavy angle-shaped member having one of its flanges 16 disposed in a vertical plane and the other flange 17 horizontally disposed and secured to the upper flanges of the diaphragms. 110

Vertical stake members 18 and diagonally extending side frame members 19 are also employed to make up the car side frame members. To the side frame members 18 and 19 are secured side boards 20. The floor of the car is substantially horizontal and includes dumping door sections such as indicated at D and fixed floor sections such as indicated at 21, 22 and 23 respectively. The fixed floor section 21, which rests upon the horizontally extending flange 17 of the lower chord member 15, extends inwardly of the car side wall slightly beyond the flange 17 and as far as the swinging edge of the door D. The fixed floor sections 22 and 23 rest upon the cross-beams and centersills respectively. Sealing plates are provided as shown at 24 and 25 to seal the openings at the front and rear edges of the doors and likewise as shown at 26—26 to seal the openings at the side edges of the doors.

A plurality of doors D are usually operated in unison by a common shaft but the description following is confined to one door for simplicity. Each door D includes a load sustaining platform preferably formed of a series of boards 27. A supporting framework for the said platform preferably includes a plurality of metallic hinge beams 28—28, in conjunction with a reinforcing beam 29 extending adjacent and under the free edge of the door, said beams 28 being united to the reinforcing beam 29 by gussets 30 and 31 in a manner to be more fully pointed out hereinafter. Each reinforcing beam 29 is preferably in the form of an angle-shaped member with one of its flanges on the underside of the door and the adjacent flange 129 depending from the door but spaced inwardly from the free edge of the door. The door at the inner edge is pivotally supported on pivots 32 carried on brackets 33, the latter being mounted above the center sill. The inner end of each hinge beam 28 is deflected upwardly above the rest of the supporting framework and to a location above the center sill and fitted with a hinge strap 34 formed with a loop 134 adapted to receive the pivot 32. At an appreciable distance from the swinging edge of the door and reinforcing beam 29 the respective hinge beams 28 commence to deflect downwardly and are extended outwardly to a point beneath the longitudinally extending, operating shaft 35 and a connection effected between each said beam 28 and a shaft 35 by means of a door supporting mechanism E.

The operating shaft 35, which is preferably of a square section, is mounted in the outer ends of the crossbeams B in suitable bearings 36, there being a circular bushing 37 provided on the shaft at each said bearing.

There are two door mechanisms E per door but inasmuch as the construction and operation of each mechanism is the same, the de-

scription will be confined to one mechanism. Each said mechanism E includes a multiple sided drum 38 fixed on the shaft and having a plurality of flat faces, preferably four in number as indicated at 39, 40, 41 and 42 respectively, the latter having an outstanding lug 43 for a purpose to be hereinafter pointed out. Outstanding from face 39 are spaced jaws 44—44. Connecting said jaws 44—44 and the co-operating door hinge beam 28 is 75 a linkage connection consisting of links as indicated at 45, 46, 47, 48 and 49 respectively, the link 45 being connected to the jaws 44—44 and the terminal two plate link 49 being in the form of a hook-shaped member and connected to the co-operating hinge beam by pivot 50.

When the flexible connection is wound upon the drum the links 45, 46, 47 and 48 are adapted to engage respectively the faces 39, 40, 41 and 42 of the winding drum. The link 48 is provided on its underside with a lug 51 adapted to engage with the lug 43 on the drum 38 thereby causing the said link 48 and drum 38 to interengage and move in unison. Said link 48 is formed to substantially correspond in width to the width of the adjacent door hinge beam 28 and acts as a spacer for the upper portion of the pair of plates constituting the link 49 and which are disposed on opposite sides of the said beams and straddle the links 45, 46, 47 and 48 when the door is in closed position. Each of the links 49 is formed with a hook-shaped upper portion as indicated at 52 which, when the flexible links are wound upon the drum 38, is disposed above the operating shaft and has its pivotal connection 53 with the link 48 disposed slightly to the far side of the axis of the operating shaft so that the load on the doors will not tend to turn the operating shaft in a direction to release the door, but on the contrary, will tend to maintain the shaft in locked position. When the links are wound upon the drum and the door is in locked position, the pivotal connection 53 is relieved of strain as the hook portion 52 of the link 49 rests upon the ledges 54—54 formed integrally upon the link block members 48 at the sides thereof. Each hook link 49, as shown, is comprised of two plate-like sections pivotally connected to the opposite sides of the inverted U-shaped hinge beam 28 and spaced by the latter. In addition, a combined re-inforcing and spacing member 55 is inserted between the flanges 128 of said beam, as shown in Figures 2 and 3. Said member 55 being of extended width also provides sufficient bearing area to prevent undue wear on the pivot 50 as the latter extends through the flanges 128 and the reinforcing member 55. It will be noted by reference to Figure 5 that the links 45, 46, 47 and 48, which wind directly on the drum, are at all times wholly maintained beyond the free edge of the door, 130

winding within a clearance limit free of the door as indicated by circle 56 shown in Figure 5, whereas the terminal hook member 49, at a certain point in the rotation of the shaft, 5 is temporarily thrown outwardly beyond this circle 56 and intersects the arc made by the swinging edge of the door as indicated at 57. It will also be noted that the hook links 49, during the opening and closing movements of 10 the door, clear the depending flange 129 of the reinforcing beam 29 and the associated gussets, due to the fact that said depending flange 129 and the associated gussets are spaced inwardly from the free edge of the door a sufficient amount for this purpose, without sacrificing the strength at the free edge of the door. With this arrangement, I not only avoid fouling of the door during the opening and closing movements thereof, but am enabled to obtain a compact arrangement while 20 at the same time permitting a wide opening for the door and ample clearance from the rail G, as shown in Figure 6.

In previous constructions such as illustrated in my U. S. Patent No. 1,056,883, dated March 25, 1913, where it has been customary to locate the shaft above the doors, the terminal hook members and co-operating spacing link extend above the load shedding plane of the door and come directly in the path of the discharging load when the door is opened but I now dispose said comparatively wide portion of the link connection entirely below the load shedding plane of the door when the door 30 is open and depress the hinge beam 28 as will be observed by reference to Figure 6 wherein it will be seen that the only portion of the link connection which is in the path of the load when the door is open is that which is adapted to wind in the plane of the hinge beam 28, i. e., links 45, 46 and 47 all of which offer comparatively small resistance to the free discharge of the load.

In a mechanism of this character where the load is suddenly dropped there is considerable strain on the doors when the same are called upon to suddenly sustain the impact of the falling load and my invention makes provision for bracing the overhanging portion of the door platform to the hinge beams 28 intermediate the pivotal axis of the door and the hinge mechanism thereof by means of the gussets 30 and 31. Gusset 30, which extends lengthwise along the deflected portion of the hinge beam 28, is secured thereto at suitable intervals to one of the depending flanges 128 by rivets 58 and it is further formed with angularly disposed flanges 59 and 159. Flange 59 lying against the underside of the door is adapted to bridge the distance between the deflected portion of the hinge beam 28 and the reinforcing beam 29, while flange 159 is secured to the depending flange 129 of the reinforcing beam 29 and to the gusset 31 as indicated by rivets at 60 and 61 respectively. Gus-

set 31 which extends lengthwise of reinforcing beam 29 is disposed substantially at right angles to gusset 30 and is sandwiched at its upper portion between the depending flange 129 of the reinforcing beam 29 and the gusset 30 and then extends downwardly being secured to the flange 159 of the gusset 30 and also to the hinge brace 28 as indicated at 62. The construction just described thus provides a door supporting framework comprising 75 beams that intersect at right angles to each other and which are rigidified at the points of intersection and insure tight joints for the door. The gusset arrangements are such, as will be obvious, to prevent longitudinal and lateral deflections of the hinge beams 28 and, conversely, to prevent deflection of the beam 29.

The door operating shaft rotating and locking means F is preferably located at the 85 end of the operating shaft and includes a ratchet wheel 63 fixedly mounted on the shaft 35, the operating shaft 35 being spaced from the level car floor a sufficient distance to accommodate the locking link 48 and cooperating terminal hook-shaped link and also the shaft locking means. A bracket member 64 is secured to the horizontal flange 17 of the lower chord member 15, said member 64 being provided with spaced depending walls 65—65, 90 between which is pivotally mounted a locking pawl 66 and a locking cam 67. Said locking pawl 66 is adapted to engage with the upper portion of the ratchet wheel 63. The shaft rotating means includes an oscillatable 95 member 68 loosely mounted on the outer side of the ratchet wheel 63 and having an operating pawl 69 pivotally mounted thereon on its inner side in the plane of the ratchet wheel 63 and engageable with the underside thereof to 100 rotate the operating shaft 35. On the outer side of the oscillatable member 68 there are a plurality of lever receiving sockets 70—70 arranged in angular relation thereby permitting the insertion of levers at varying angles. 110 The disposition of the locking means in this manner in the space between the shaft and floor of the car thus permits of the employment of a compact operating and locking means as a single ratchet may then be used for 115 both rotating and locking the shaft and, furthermore, the parts are thoroughly protected and mounted on substantial members of the car body.

With the arrangement hereinbefore described, it will be observed that the full load carrying capacity of the car is obtained while at the same time the operating shaft and associated linkages are adequately protected and that there are no sloping sheets required which would be subject to injury from clam shell buckets and the like, frequently used in the unloading of cars of this type. It will further be noted that the operating shaft is particularly free from injury due to the dis- 130

charging load, notwithstanding that it is below the floor level. The linkages also are so arranged, as previously pointed out, as to obtain the least interference with the dis-
5 charging load, the hook links particularly and adjacent links 48 being below the plane of the upper surface of the door when in open position.

By providing the hinge beams with the de-
10 flected outer portions as hereinbefore de-
scribed, and attaching the hook links as shown, I am enabled to obtain a compact ar-
rangement while at the same time locating the operating shaft below the floor level.

15 This arrangement also provides the necessary wide door opening and at the same time sufficient clearance is provided between the door beams and the rail to prevent fouling. An additional advantage, particularly from a
20 mechanical strength standpoint, which re-
sults from the particular hinge connection which I have provided and the particular form of deflected hinge beam, is the fact that there is a large upward thrust opening as in-
25 dicated by the arrow in Figure 6, which counteracts, to a large degree, any tendency of the hinge beams 28 to bend under load when the doors are in open position.

I have herein shown and described what I
30 now consider the preferred manner of carrying out my invention, but the same is merely illustrative and I contemplate all changes and modifications that come within the scope of the claims appended hereto.

35 I claim:

1. In a railway car, the combination with a substantially level car floor, said floor including a fixed floor section and a movable floor section; of a shaft mounted beneath the
40 fixed floor section; a beam extending from the movable floor section to a position beneath the fixed floor section; supporting means connecting said shaft and beam, said supporting means including a series of links and a termi-
45 nal hook member, connected with said links and pivotally connected with said beam, said links being adapted to wind around the shaft within a clearance limit beyond the free edge of the door, said terminal hook member, when
50 the door is in its closed position, being adapted to lie between the shaft and the fixed floor section with its point of attachment with the links, contained within said clearance limit, said terminal hook member during the initial
55 opening movement of the door being adapted to have a portion thereof moved beneath the movable floor section, while its pivotal point of attachment with the beam is contained within said clearance limit beyond the swing-
60 ing edge of the door.

2. In a dump car, the combination with a load supporting door; of an operating shaft below the level of the door when the latter is in closed position; a polygonal drum on said
65 shaft, a jointed link connection between the

drum and door, said jointed link connection including link members corresponding in number to the number of faces on the drum and a terminal hook link connection, the joints of the link connection being adapted 70 to move in a path clear of the door and the terminal hook member having a portion thereof adapted to intersect the arc made by the swinging edge of the door, said terminal hook link having a portion temporarily mov-
75 able to a position beneath the door during the closing movement of the latter while its point of attachment with the links is confined in a path clear of the door.

3. In a railway car, the combination with a dumping door; of an operating shaft dis-
posed adjacent the free edge of the door when closed and out of the path of movement there-
of; beams on the door extending outwardly and downwardly beneath the operating shaft 80 when the door is closed, said beams commencing to bend downwardly at an appreciable distance inwardly of the free edge of the door; and winding link mechanisms includ-
85 ing link members adapted to wind around the shaft in the plane of the door beams and hook link sections, said sections being spaced at their lower extremities by the door beam and at their upper end by one of the link
90 members formed of a width to act as a spacing member whereby the hook link sections will straddle the winding links, said sections and spacing link, when the doors are in opened position, being disposed below the top plane of the door.

4. In a railway car, the combination with a dumping door; of an operating shaft dis-
posed adjacent the free edge of the door when closed and out of the path of movement there-
of; beams on the door extending outwardly 105 and downwardly beneath the operating shaft; winding link mechanisms adapted to wind around the shaft in the plane of the door beams; pairs of connecting hook members at-
110 tached to said beams, each pair of connecting hook members together presenting a widened portion adapted to straddle the beam and also straddle the link members when the door is in closed position, the widened portion present-
115 ed by each pair of links being disposed below the level of the load shedding surface of the door when the latter is in open position.

5. In a dump car, the combination with a dumping door; of an operating shaft dis-
posed below the level of the door when closed and adjacent the free edge thereof; a beam member extending crosswise of and on the un-
derside of the door, said beam member being deflected downwardly and outwardly from a point inwardly of the free edge of the door to 120 a point beneath the shaft when the door is closed; and supporting mechanism extending from said shaft to said beam, said mechanism including the hook member connected at one end to said beam and at its opposite end to 125

said supporting mechanism, said hook member when the door is in closed position resting on said shaft, and during initial opening movement of said door having a portion extending beneath said door, said hook member and supporting mechanism, when the door is in open position, being spaced clear of the free edge of said door.

6. In a dump car, the combination with a dump door; of an operating shaft; a door beam on the underside of the door, said beam being of inverted U-shaped section; a filler member disposed within the said U-shaped beam and secured thereto; winding link members disposed in the plane of the beam; terminal hook link members disposed on either side of the beam and secured to the said winding link members; and securing means passing through the said terminal link members, door beam and filler member.

7. In a dump car, the combination with a dumping door; of an operating shaft adjacent the free edge of the door; a hinge beam secured to the underside of the door, said hinge beam having a pivotal connection with the car body at a point above the main plane of the beam, said beam having also its outer end deflected downwardly and outwardly beneath the operating shaft; and self-locking winding mechanism connecting the operating shaft and hinge beam.

8. In a dump car, the combination with a dumping door; of an operating shaft disposed beyond the free edge of the door and below the level of the door when closed; a beam member adapted to reinforce the free edge of the door and extending substantially in parallelism with the said shaft; a hinge beam member extending outwardly and downwardly beneath the first named member, said hinge beam member being deflected downwardly from a point beginning an appreciable distance from the beam reinforcing the free edge of the door; and a flexible connection between said shaft and hinge beam member.

9. In a dump car, the combination with a dumping door; of an operating shaft disposed below the level of the door when closed and adjacent the free edge thereof; a hinge beam member on the underside of the door, said beam member being deflected downwardly and outwardly beneath the shaft, said beam member commencing to deflect at an appreciable distance from the free edge of the door; a reinforcing beam member extending along the free edge of the door above the hinge member, said reinforcing beam member consisting of an angle shaped section having one flange lying against the door and the adjacent flange thereto outstanding from the door; and bracing means adapted to brace the depending flange of the reinforcing member to the hinge beam, said bracing means including sections disposed at right angles to each other and extending lengthwise of the respective beams

and secured to the said beams and to each other.

10. In a dump car, the combination with a dumping door; of an operating shaft disposed beyond the free edge of the door when closed and below the level of the same; a beam adapted to reinforce the free edge of the door, said beam having a flange lying against the under surface of the door and a depending flange spaced inwardly from the free edge of the door; a hinge beam extending across the plane of said reinforcing beam and having a downwardly extending portion; a gusset extending lengthwise of the reinforcing beam and secured to the depending flange of the reinforcing beam, said gusset being extended downwardly and outwardly and secured to the downwardly extending portion of the hinge beam; winding link mechanism connecting the shaft and the hinge beam, said link mechanisms including a hook shaped member adapted to move, in the path of the door temporarily beneath the portion of the reinforcing beam lying against the door.

11. In a dump car, the combination with a dumping door; of an operating shaft disposed beyond the free edge of the door when closed and below the level of the same; a beam adapted to reinforce the free edge of the door and extending substantially in parallelism with the operating shaft; a hinge beam member extending outwardly and downwardly beneath the first named reinforcing beam, said hinge beam commencing to deflect downwardly at a point an appreciable distance from the free edge of the door; a gusset member extending lengthwise of the hinge beam member and adapted to bridge the distance between the deflected portion of the hinge beam member and the reinforcing beam and secured thereto and a second gusset secured to the first named gusset and to the hinge beam; and a connection between the shaft and hinge beam.

12. In a dump car, the combination with a dumping door; of an operating shaft disposed below the level of the door when closed and adjacent the free edge thereof; a hinge beam member on the under side of the door, said hinged beam member being deflected downwardly and outwardly beneath the shaft; self-locking winding mechanism connected to the shaft and door beam respectively, said mechanism including a hook shaped member adapted to move at a certain point in the rotation of the shaft to a position beneath the door; a reinforcing beam member extending along the free edge of the door, said beam member being so disposed as to clear the hook shaped member during its movement beneath the door; a gusset member extending lengthwise of the reinforcing beam and secured thereto and to the downwardly deflected portion of the hinge beam member, said gusset being disposed inwardly

of the path of movement of the hook member; and a second gusset extending at right angles to the first named gusset and adapted to brace the said gusset to the hinge beam 5 member.

13. In a dump car, the combination with a dumping door, of an operating shaft disposed beyond the free edge of the door when closed, and below the level of the same; a 10 hinge beam extending outwardly and downwardly beneath the operating shaft, said hinge beam commencing to deflect downwardly at an appreciable distance from the free edge of the door; winding mechanism 15 adapted to connect the shaft and the downwardly deflected portion of the hinge beam; a reinforcing beam disposed beyond the path of movement of the door connection parts; a gusset member extended lengthwise of the 20 said reinforcing beam and secured to the downwardly deflected portion of the hinge beam; and a second gusset extending lengthwise of the hinge beam and adapted to engage with and be secured to the first named 25 gusset centrally of the same.

14. In a dump car, the combination with a car side having a lower chord presenting vertical and horizontal flanges, the horizontal flange being of extended width; of a dumping door; a shaft mounted below the plane 30 of the door when in closed position and disposed beneath the marginal flange of the lower chord and spaced an appreciable distance therefrom; a beam on the door extending outwardly and downwardly beneath the said operating shaft; and winding mechanism connecting the shaft and beam, said mechanism including members adapted to 35 assume a position between the shaft and said marginal flange of the lower chord whereby the shaft is automatically locked with the door in closed position, said shaft being rotatable in a direction away from the free edge 40 of the door to wind said mechanism thereon.

15. In a dump car having a dumping door 45 arranged to assume horizontal floor position when closed and having also a flat floor section in line with said door opposite the free edge thereof; the combination with a door operating shaft disposed directly beneath and 50 protected by said fixed floor section; of means rigid with and extended downwardly and outwardly from the free edge of said door; and a flexible winding mechanism interposed between said shaft and said means and adapted to be wound on said shaft when the latter is rotated in a direction away from the free edge of said door, said winding mechanism including hook members having the 55 ends of their hook portions pivotally connected to said winding mechanism and having their opposite ends pivotally connected to the ends of said means.

16. In a dump car, the combination with a dumping door hinged along one edge thereof; of an operating shaft located adjacent the free edge of the door when the latter is in closed position; a self-locking winding mechanism attached at one of its ends to said shaft, the opposite end of said winding mechanism comprising a hook-shaped link, said mechanism being adapted to wind on said shaft when the latter is rotated in a direction 60 away from the free edge of said door; means, rigid with said door, to which said hook-shaped link is attached, said winding mechanism supporting the free edge of the door in its open position and said means and hook-shaped link being so arranged that, in open 65 position of the door, said hook-shaped link is disposed entirely below the plane of the upper surface of the door, and said hook shaped link and winding mechanism are spaced clear 70 of the free edge of said door.

In witness that I claim the foregoing I 75 have hereunto subscribed my name this 18th day of September, 1926.

ARGYLE CAMPBELL.
